(57) CLAIM

The ornamental design for a food storage container as shown and described.

DESCRIPTION

FIG. 1 is a front, right-side and top perspective view of a food storage container showing our new design;

FIG. 2 is a front, left-side and top perspective view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The rear side of the food storage container is identical to the front side.

The dashed broken lines depict portions of the food storage container that form no part of the claimed design.

1 Claim, 7 Drawing Sheets
